UNITED STATES PATENT OFFICE.

JOHN A. WHERRY, OF NEW ORLEANS, LOUISIANA.

COLLATING DEVICE FOR TYPE-WRITERS AND ADDING-MACHINES.

1,324,632.

Specification of Letters Patent.

Patented Dec. 9, 1919.

Application filed May 5, 1919. Serial No. 284,775.

To all whom it may concern:

Be it known that I, JOHN A. WHERRY, a citizen of the United States, residing at New Orleans, in the parish of Orleans and State of Louisiana, have invented certain new and useful Improvements in Collating Devices for Type-Writers and Adding-Machines; and I do hereby declare the following to be a full, clear, and exact description 10 of the invention, such as will enable others skilled in the art to which it appertains to make and use the same.

This invention relates to a collating device for typewriters and adding machines, 15 and particularly to adding machines without the typewriter features, wherein a revoluble platen is used for ledger posting and statement work.

The invention is in the nature of an improvement on the invention disclosed in my co-pending application, Serial No. 289,120, filed April 10, 1919.

The primary object of the invention resides in the provision of a collating device 25 on which the working sheets may be assembled or collated and carried to the printing position on the typewriter on an adding machine without disarrangement.

In the drawing:—

30 Figure 1 is a front elevation of my device with the vertical webs of the sheet clamps shown in section so as to more clearly distinguish the same;

Fig. 2 is a rear elevation;

35 Fig. 3 is an end elevation showing both of the sheet clamps raised;

Fig. 4 is a similar elevation showing the under sheet clamp lowered;

40 Fig. 5 is an elevation showing both of the clamps lowered;

Fig. 6 is a sectional view showing both of the clamps raised;

Fig. 7 is a sectional view showing the under clamp lowered;

45 Fig. 8 is a sectional view showing both of the clamps lowered; and

Fig. 9 is a view looking at one of the brackets with the clamps shown in section to more clearly distinguish the same.

50 As in the invention disclosed in the above-referred to co-pending application, the device includes a board 1, which is supported on the inner carriage of the typewriter or

adding machine by standards 2 and 3, which are bent from the material of the board itself. A pair of brackets 4 are secured on the front faces of the collating board 1, adjustably by thumb screws 5, which screws extend through slots 6 in the board whereby the brackets may be moved to or away from each other. On each of these brackets 4 an angular sheet clamp 7 is mounted for movement to and away from the board 1, the sheet clamps being held in position on the brackets by screws 8, which extend through slots 9 in the vertical webs of the sheet clamps. A rotary rod 10 is mounted on the rear of the board in brackets 11 and sleeves 12 are mounted on the ends of this rod 10. These sleeves are adapted to 70 rotate and to slide longitudinally of the rod, but are capable of being held against relative rotative movement by thumb screws 13, which are mounted in the sleeves and project into a slot 14 in the rod. Thus, as in the 75 above referred to application, the sleeves may have either relative rotative movement on the rod, or may be prevented from having such movement, but permitted to have relative longitudinal movement by adjustment of 80 the thumb screws 13. The springs 15 encircle the rod 10 and are secured to the thumb screws 13 and at their other ends to thumb screws 16 carried by the rod and normally tend to move the sleeves toward each other and to rotate the same on the rod. Arms 17 project from the sleeves 12 through slots 18 in the collating board and are in the form of bell cranks, each having a straight portion 19, which engages in a 90 diagonally disposed slot 20 in the vertical web of the under sheet clamp 7, which slots have notches 21 therein for the engagement of the straight portions 19 of the arms 17, whereby the clamping members 7 will be 95 maintained in raised relation to the collating board 1 in the manner described in the above-referred to co-pending application. Secured to the rear of the collating board at 22 and to a thumb screw 23 on the rod 100 10, is a spring 24, which normally tends to rotate the rod 10 so as to throw the clamping members 7 against the front faces of the board. This thumb screw 23 is provided with a projecting bill 24' which is adapted 105 to extend into an opening in the board 1 to

prevent the rotation of the rod 10 under the influence of the spring 24. A lock nut 25 is mounted on this thumb screw 23 and is so located that it will prevent the bill of the thumb screw from projecting beyond the working face of the board 1 and will also prevent the entire withdrawal of the thumb screw from the rod.

Secured to the bracket 4 by screws 26, are springs 27, which tend to cause the uniform movement of the ends of the sheet clamping members 7 toward the face of the board. Projecting downwardly from the brackets 4 are feed arms 28, having feed rollers 29 thereon, which operate against the platen 30.

A second or upper sheet clamping member 31 is associated with each of the sheet clamping members 7. This upper sheet clamping member is of angular form and is slidably mounted on the sheet clamping members 7, being guided in its movement by screws 32 which project through slots 33 in the vertical web of the same. This vertical web is also provided with slots 34 for the accommodation of the heads of the screws 8 on which the sheet clamping member 7 operates. Springs 35, which are secured to the brackets 4 and project through openings in the vertical webs of the sheet clamping members 31, normally tend to maintain these members in their raised positions.

Slides 36 are mounted on the brackets 4 by means of set screws 37, which project through slots 38 in the slides, thus permitting the slides to have movement longitudinally of the brackets. Each of these slides is provided with an upwardly extending or bowed portion, beneath which the straight portion 19 and the adjacent arm 17 extends. From one end of each of the slides a pin 40 extends, which pin projects through a diagonally disposed slot 41 in the vertical web of the upper sheet clamping member 31, and at the other end of each of the clamps a second finger 42 is provided, which extends through a similar diagonally arranged slot 43 in the clamping member 31. Each of these slots is provided with a notch 44 for the reception of the fingers, whereby when the fingers are engaged in the notches, the clamping member will be maintained in its raised position, that is to say, in spaced relation to the board and to the lower clamping member. It will be noted that the vertical web of each of the upper clamping members 31 is cut away at 45, to accommodate the end of the adjacent arm 17.

When the rock arm 17 is pressed upwardly it engages with the loop of the slide 36 and pushes said slide upwardly. The upward movement of this slide raises the sheet alining and clamping members 7 away from the board and the sheet alining and

clamping members 31 away from the first 65 mentioned members 7. When the rock arms are raised in the above manner they engage in the notches 21, thus maintaining the upper and lower sheet alining and clamping members 7 in their raised positions. The 70 pins 40 engage in the notches 44 and maintain the upper sheet alining and clamping members 31 in their raised positions.

A sheet of paper is inserted in the machine in the usual manner and turned up by the 75 platen knob under the feed rollers 29. The work sheet passes under the brackets 4 and the clamps 7 and 31. This work sheet is then alined at right angles with the printing position on the platen by abutting said sheet 80 against the under side of the vertical webs of the brackets 4. The feed rollers of the typewriter are then released and the work sheet is held in position on the platen and on the collating board by the feed rollers 29 85 of the collating board 1.

The second work sheet with the carbon paper is inserted around the platen by hand, but this second sheet does not pass under the feed rollers 29 of the collating board. This 90 second sheet is placed beneath the sheet alining and clamping members 7, and if ruled lines are on the work sheet it is alined at right angles with the printing position of the platen by forcing the ruled lines of the 95 work sheet in line with one of the side edges of said members 1 and the proper printing position is placed under the graduated lines 31' on the members 31. If the work sheet is not ruled the desired printing position is alined by one of the graduations on the members 31 and the starting point and the line is alined by the edges of the lower sheet alining and clamping member 7. The rock arm is then lowered, which causes the movement of the lower member 7 toward the board and firmly holds the work sheet with the carbon paper firmly in place upon the first sheet inserted. The third work sheet with the carbon papers is inserted in the 100 same manner as the second, but this sheet is placed on top of the members 7 and brought in proper position with the second work sheet and the side edges are abutted against the vertical portions of the members 7 105 whereby it is lowered at right angles with the printing position of the typewriter. The upper sheet alining and clamping members 31 are then lowered by pressing down on the slide 36. Thus the third sheet and carbon are clamped in place. The feed rollers of the typewriter are then raised against the work sheets, which holds them in proper position on the platen. The rock arm 17 is then raised, which in turn raises the slide 36, 110 whereby the sheet alining and clamping members 7 and 31 are raised, thus freeing the work sheets. The work sheets may then be 115 120 125

turned down to the proper printing position on the typewriter by the platea knob, and the operator may then proceed with the writing or printing. The work sheets may be fed either upwardly or downwardly under the brackets 6 and the members 7 and 31.

- After the writing or printing has been completed the feed rollers of the typewriters are lowered from the work sheets and the 10 second and third sheets are moved from the typewriter and collating board. The first sheet inserted, however, remains in its proper position on the typewriter and on the collating board, being held in this position by the feed rollers 29. This first sheet is generally used as a proof sheet. In other words all records that are printed or written on the second and third sheets are recorded on the proof sheets.
- 20 It is to be understood, of course, that various modifications in the details of construction may be made within the scope of the claims.

Furthermore, it is to be understood that 25 the collating is not confined to three sheets, as the device may be used in connection with the collating of various numbers of sheets.

What I claim is:

1. A collating device including a board, 30 superimposed sheet clamping and alining members arranged on the upper side of the board, and means for raising said members from the board.
2. A collating device including a board, 35 superimposed sheet clamping and alining members arranged on the upper side of the board, means for raising said members from the board, and means for raising the upper members from the lower members.
3. A collating device including a board, 40 brackets mounted on the board, upper and lower sheet clamping and alining members supported by said brackets, means normally tending to move the lower members toward the board, means tending to move the upper members toward the lower members, and means for raising the lower members from the board.
4. A collating device including a board, 45 brackets mounted on the board, means for adjusting the brackets toward and away from each other, upper and lower sheet clamping and alining members supported by said brackets, means normally tending to move the lower members toward the board, means tending to move the upper members toward the lower members, and means for raising the lower members from the board.
5. A collating device including a board, 50 brackets mounted on the board, upper and lower sheet clamping and alining members supported by said brackets, resilient means normally tending to move the lower members toward the board, means tending to
- move the upper members toward the lower 65 members, and means for raising the lower members from the board.
6. A collating device including a board, 70 brackets mounted on the board, upper and lower sheet clamping and alining members supported by said brackets, means normally tending to move the lower members toward the board, means tending to move the upper members toward the lower members, means for raising the upper members from the 75 lower members, and means for raising the lower members from the board.
7. A collating device including a board, 80 brackets mounted on the board, upper and lower sheet clamping and alining members supported by said brackets, means normally tending to move the lower members toward the board, means tending to move the upper members toward the lower members, means for raising the lower members from the 85 board, and means for maintaining the lower members in their raised positions.
8. A collating device including a board, 90 brackets mounted on the board, upper and lower sheet clamping and alining members supported by said brackets, means normally tending to move the lower members toward the board, means tending to move the upper members toward the lower members, means for raising the lower members from the 95 board, and independent means for maintaining the upper members raised from the lower members.
9. A collating device, including a board, 100 upper and lower sheet clamping and alining members, means for raising the lower members from the board, and for simultaneously raising the upper members from the lower members.
10. A collating device including a board, 105 upper and lower sheet clamping and alining members, means for raising the lower members from the board and for simultaneously raising the upper members from the lower members, said means being operative to permit the independent lowering of the upper and lower members.
11. A collating device including a board, 115 upper and lower sheet clamping and alining members, means for raising the lower members from the board and for simultaneously raising the upper members from the lower members, said means being operative to permit the independent lowering of the upper and lower members, and means for lowering 120 the upper sheet clamping and alining members.
12. A collating device including a board, 125 upper and lower sheet clamping and alining members, means for raising the lower members from the board and for simultaneously raising the upper members from the lower members, said means being operative

to permit the independent lowering of the upper and lower members, and resilient means for lowering the upper sheet clamping and alining members.

5 13. A collating device including a board, upper and lower sheet clamping and alining members, means for raising the lower members from the board and for simultaneously

raising the upper members from the lower members, means for independently maintaining the upper and lower members in their raised positions, said means being operative to permit the independent lowering of the upper and lower members. 10

In testimony whereof I affix my signature. 15

JOHN A. WHERRY.
